UNITED STATES PATENT OFFICE.

SAMUEL L. ALLEN, OF MOORESTOWN, NEW JERSEY.

METAL WHEEL.

SPECIFICATION forming part of Letters Patent No. 730,591, dated June 9, 1903.

Application filed July 11, 1900. Serial No. 23,174. (No model.)

To all whom it may concern:

Be it known that I, SAMUEL L. ALLEN, a citizen of the United States, and a resident of Moorestown, State of New Jersey, have invented certain new and useful Improvements in Metal Wheels, of which the following is a full, clear, and exact description, reference being had to the accompanying drawings, forming part of this specification.

10 This invention relates to certain improvements in the construction of metal wheels, and has for its principal object to simplify and cheapen the construction and at the same time produce a wheel having great strength and durability.

15 In order that my invention may be fully understood by those skilled in the art to which it appertains, I will proceed to describe it, reference being had to the accompanying drawings, in which—

Figure 1 is a side elevation of a wheel embodying my invention, the central hub or bushing being shown in section. Fig. 2 is an enlarged sectional view taken substantially 20 on a radial line through the center of the hub and through a continuous portion of the rim at the end of a spoke. Fig. 3 is an elevation, on an enlarged scale, of the hub, one of the hub-plates being removed for the purpose 25 of illustrating the inner portions of the spokes. Fig. 4 is a sectional view taken about on the line 55 of Fig. 3. Fig. 5 is a detail view of one of the hub-plates, illustrating the grooves formed on their inner faces; and Fig. 6 is a 30 detail sectional view taken about on the line 35 77 of Fig. 5.

The rim A of the wheel consists of a strip of flat sheet steel or iron bent to circular form in any well-known manner.

40 In the center of the rim A are punched a series of apertures a, equidistant apart, corresponding in number to the number of spokes desired in the wheel, the said apertures being punched in such a manner as to form the flanges a' on the under side of the rim around each aperture.

The spokes comprise the steel rods B, of a diameter corresponding to the diameter of the apertures a at their outer ends, while 45 their intermediate portions are preferably flattened out in the shape illustrated in the drawings. Each pair of spokes is made of a sin-

gle rod bent at its central portion in the manner illustrated most clearly in Fig. 3 of the drawings.

55 Near the outer ends of each of the spokes B is formed a shoulder c, which is integral with the spoke, as shown in Fig. 2 of the drawings. These shoulders should be so located with respect to the ends of the spokes as to 60 bear against the flanges a' when said spoke ends are inserted in the apertures a of the rim. After the ends of the spokes are inserted in the rim, as above described, they are upset or riveted and made flush with the 65 outer surface of the rim, the curved or rounded edge of the aperture affording a space into which the end of the spoke spreads as it is upset or riveted.

The hub comprises two plates D D', which 70 may be forged or stamped out of sheet metal. The plates D D' are each provided with radial wedge-shaped grooves d, corresponding in shape to the contour of the spoke, and are adapted to embrace a portion of the said 75 spokes when the said two plates are clamped together.

At the inner ends of each of the grooves d I provide a substantially circular groove d', concentric with the axis of the wheel and 80 merging into and forming a continuation of the grooves d. These grooves d and d' have inclined or wedge-shaped walls, which bind against the sides of the spokes B.

The centers of the plates D D' are provided 85 with the apertures f, struck out in such a manner as to form the flanges f', which when the two plates are clamped form a central bore for the bushing G. This bushing G is provided with a flange g near one end, which 90 bears against the end of the flange f', while its other end is screw-threaded for the reception of a nut g². A central bore or aperture is provided through the bushing G for the passage of the wheel-axle.

95 In Fig. 2 of the drawings I have shown the lower plate D' as having a bevel-gear d² formed integral therewith, also having the central sleeve or bushing formed integral with said section D'. When this form is used, I 100 form on the inner face of the plate D' between the radial grooves d the studs e, having their ends reduced and screw-threaded, as shown in Fig. 2 of the drawings. The op-

positely-disposed plate D is provided with apertures which register with the studs e when both plates are placed in position, the screw-threaded shanks extending through 5 said apertures and adapted to receive the nuts e², by means of which the two plates are securely held together.

When it is not desired to use bevel-gear d², both of the plates D and D' are made alike 10 and are clamped together by the stud-bolt e'. (Shown in detail in Fig. 6 of the drawings.) Thus when the spokes are riveted in the rim, as heretofore described, and the plates D D' are placed in position around the inner portions 15 of the spokes and clamped together by means of the bolts e and nuts e² and the bushing G the inclined shoulders or side walls of the grooves d and d' will come in contact with and bind against the sides of the spokes 20 B with a wedge effect, the grooves d' serving to draw the spokes toward the center of the wheel and against the bushing G and securely hold them in position.

The plates D and D' are preferably made 25 of sheet-steel struck up in the desired shape, having the flanges f' drawn thereon in the process of stamping.

The rim A is formed of a single strip of metal, as heretofore described, and after 30 bending into a circular form the meeting edges overlap, as illustrated in Fig. 1 of the drawings.

The shape of the inner portions of the spokes may be varied or modified in form so 35 long as the "wedge" feature is retained, and other changes might be made in the details of my wheel without departing from the spirit and scope of my invention.

Having thus described my invention, what 40 I claim, and desire to secure by Letters Patent, is—

1. In a metal wheel, the combination with the rim of spokes secured therein, each pair of spokes being composed of a single rod bent 45 to form an angle at its center, and having inclined or tapering edges formed thereon, a pair of hub-plates adapted to embrace the angularly-disposed and inner portions of the spokes, and having inclined or wedge-shaped 50 indentations formed therein in which the spokes rest, and means for clamping said plates together, substantially as described.

2. In a metal wheel, the combination with the rim, of spokes formed in pairs each pair comprising a single rod secured at each end 55 to the rim and having its central portion bent to form an angular intermediate section, the inner straight portions and angularly-disposed portions of each spoke being flattened out to form wedge-shaped edges on each side, a pair of hub-plates having wedge-shaped grooves or indentations adapted to receive the inner portions of the spokes, and clamping-bolts for securing the two plates together, substantially as described. 60

3. In a metal wheel, the combination with the rim, of spokes formed in pairs each pair comprising a single rod secured at each end to the rim and having its central portion bent to form an angular intermediate section, the 70 inner straight portions and angularly-disposed portion of each spoke being flattened out to form wedge-shaped edges on each side, a pair of hub-plates having wedge-shaped grooves or indentations adapted to receive 75 the inner portions of the spokes and having central openings formed therein, a sleeve or bushing adapted to said opening and means for securing the same in position, substantially as described. 80

4. The combination with the rim, of spokes formed in pairs each pair comprising a single rod secured at each end in the rim, having its central portion bent to form a curve substantially concentric to the center of the wheel, 85 and having inclined or wedge-shaped edges formed thereon, a pair of hub-plates having radial grooves provided with inclined or wedge-shaped side walls and having central apertures formed in said hub-plates and concentric grooves or indentations formed around 90 said apertures having their outer walls inclined and adapted to bear against the curved portion of each pair of spokes, a bushing passing through the hub-apertures, and means for securing the parts together, substantially as described. 95

In witness whereof I have hereunto set my hand this 9th day of July, A. D. 1900.

SAMUEL L. ALLEN.
